UNITED STATES PATENT OFFICE

2,484,940

VALVE

George W. Franzheim, Dunkirk, N. Y.

Application July 3, 1947; Serial No. 758,958

4 Claims. (Cl. 137—139)

1

This invention relates to valves, and more particularly, has reference to an improved automatic cut-off valve particularly designed for mounting in association with a gas line, in position automatically to cut off the supply of gas under predetermined conditions.

Reference is had in this connection to my Patent No. 1,727,503, covering such a valve, the application in the present instance referring to a novel and improved construction thereof.

In the art, valves are known that are adapted to remain normally open when gas is flowing under proper pressure, said valves closing under a decrease in pressure, where the pressure falls below a predetermined amount, the valve thus serving to cut off the supply of gas completely until the undesirable condition described can be remedied. Such an operation is described in my patent.

However, the primary object of the present invention is not only to achieve the result stated above, whereby the valve will automatically close upon a lowering of the flow of gas below a predetermined pressure, but also to cause the valve to be automatically operated to close the gas supply in the event of such instances as a fire occurring in the basement in which the valve unit is mounted, a flood in the basement, explosion, or similar serious accidents.

Additionally, it is an important object of the invention to provide a valve of the type described that is also readily operable by hand, for the purpose of cutting off the gas supply, from some exterior point, as for example, from a pull box located at another point either within or without the building in which the unit is mounted. This is particularly desirable in the event of fire, permitting the firemen to close the gas supply, for example, from a point outside the building in which the fire is located.

Additionally, I provide in my improved device means for actuating an alarm, such as a signal bell, light, or the like, upon the closing of the valve for any reason.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing, the single figure illustrated is a view, partly in side elevation and

partly in vertical section, of the improved device.

Referring to the drawing in detail, 5 designates generally a valve casing of substantially hollow formation, through which gas is normally permitted to pass. At one end, this is provided with an annular flange 6, in engagement with flange 7 on a coupling 8 for an outlet pipe (not shown), bolts 9 or similar fastening means being used to connect the coupling to the casing. The coupling 8, as will be known, may be threaded for ready connection to the outlet pipe.

At its other end, the casing 5 is provided with an inlet 10, that is adapted to be closed by the valve 11. Valve 11 is of the swinging type, being pivoted on pin 12 suitably journaled in the wall of the casing, by means of the arm 13. A facing 14 of specially treated leather of a type known in the art is preferably provided on the valve 11, and the valve seats, when in position to close the inlet 10, in valve seat 15.

Normally, when gas is flowing through the inlet 10 into the casing 5 under a normal predetermined pressure, the valve 11 is swung rearwardly to the position shown in the drawing, the valve being so designed as to normally hang in an open position.

Extended transversely through the casing 5, and suitably journaled in the wall thereof, is a pin 16, to which is attached exteriorly of the casing 30 5 a lever 17. Lever 17 is provided with the weight 18, which may be mounted adjustably on the lever 17 at a desired point. Thus, on rotation of the pin 16, the lever 17 will swing in an arc.

Attached to the pin 16 interiorly of the casing 35 5 is a hook 19, which is also a cam 20. When the hook is swung toward the inlet 10, the cam portion thereof engages the rear of the valve 11, and at the same time, the lever 17 having the weight 18, is swung in its arc, the lever and weight 40 providing the necessary force whereby the hook 19 is swung rearwardly, causing the valve 11 to seat in position to close the inlet 10, in which position it is retained under pressure of the cam 20, until such time as the lever 17 is raised by hand.

Normally, the hook 19, as shown in the drawing, is engaged and retained in the position shown by a latch lever 21 within the casing 5, which is pivoted at one end on pin 22, that can be journaled in ears 23 of the casing. The latch lever 21 is also pivotally connected, intermediate its ends, at 24 to one end of a stem 25, that projects through the opening 26 communicating between the valve casing and a diaphragm casing, to be described hereinafter.

The end of the stem 25 that projects into the diaphragm casing is provided with a disc 27, to which is connectable disc 28, as by bolt 29 or the like. Between the discs 27 and 28 is retained the center portion of a diaphragm 30.

The diaphragm casing in which the diaphragm 30 is mounted comprises a lower portion 31 and an upper portion 32 connectable to each other by bolts 33 or similar fastening means, said fastening means serving additionally to mount the diaphragm 30 within the diaphragm casing.

Under normal conditions, gas flowing through the casing 5 will also move through the opening 26, which, as may be readily observed from the drawing, is of greater diameter than the diameter of the stem 25, so as to permit an unimpeded flow of gas from the casing 5 to the diaphragm casing. When the gas is flowing under a proper predetermined pressure, it serves to press upwardly against the bottom of the diaphragm 30, and thus holds the stem 25 in normally raised position, whereby latch lever 21 will retain hook 19 out of engagement with the valve 11. However, when the gas pressure drops below the predetermined point, the relaxing of pressure against the diaphragm 30 immediately causes the stem 25 to lower, releasing hook 19, whereupon lever 17 having weight 18 will swing rearwardly, causing the cam 20 to force the valve into position to close the inlet 10.

The construction of the device described above is substantially as shown in my patent, and basically comprises the valve unit described in the patent, wherein the valve will close under a lowering of pressure of gas flowing therethrough.

In the present invention, however, I also provide a tubular extension 34 projecting from the upper portion 32 of the diaphragm casing. In the wall thereof, I form opening 35 that serves as an inlet opening for water. Thus, water rising around the unit, as in the case of a flooded basement or the like, will enter the inlet opening 35, and will proceed through opening 36 communicating between the interior of the tubular extension, and the interior of the diaphragm casing. Thus, it is seen that the admission of a quantity of water through the opening 36, will bring pressure against the upper surface of the diaphragm 30, and upon the accumulation of a sufficient amount of water bearing against the diaphragm, the diaphragm will be lowered, closing the valve, even though the gas is flowing through the unit under proper and normal pressure. A desirable safety feature is thus obtained. The opening 35 also constitutes an air vent, since the upper portion of the diaphragm casing should be properly vented at all times during normal use of the valve.

The opening 36 is of greater diameter than the diameter of a rod 37 projected therethrough. One end of this rod appears against the disc 28. Interiorly of the tubular extension 34, the rod 37 is preferably provided with a lug 38 constituting an abutment for one end of a coil spring 39 that normally is held under restraint.

The outer end of the tubular extension 34 is formed with a threaded opening 40, which is closed by plug 41. Plug 41 constitutes the abutment for the other end of the spring 39. The rod 37, as will be seen, projects through the plug 41, and it is slidable therein. The rod 37, on its projecting end, is provided with a head 42, and interposed between the head 42 and the outer surface of plug 41 is a spacer 43 that is formed of a fusible material, such as will melt when the surrounding temperature reaches a prescribed num-

ber of degrees, such as, for example, approximately 400° F.

By reason of this construction, should there be a fire in the vicinity of the unit, the spacer 43 will melt as stated, whereupon the spring 39, being no longer held under normal compression, will expand, the lower end thereof forcing the end of rod 37 positioned against disc 28 inwardly, thereby lowering the diaphragm 30 a sufficient amount to release hook 19.

A water-soluble spacer 43' is also mounted on rod 37. This supplements vent 35 in closing the valve in case of flood.

Additionally, means are provided for effecting a closing of the valve from some remote point, as for instance, from a pull box positioned exteriorly of the building. This is desirable in the case, for example, of a fire within the building, it being desirable that the gas supply be cut off quickly and easily. A housing 44 is formed on the upper portion 32 of the diaphragm casing, in which is pivotally mounted, as on an ear or ears 45, a lever 46, which is so mounted intermediate its ends. At one end, lever 46 is pivotally connected to a rod 47, projecting through a communicating opening between the housing 44 and diaphragm casing, so as to bear against the disc 28. Spring 48 is interposed between the lever 46 and said opening, and the rod 47 passes through said spring.

The other end of the lever 46 is connected to one end of a flexible cable 49, extended through tube 50, tube 50 being connected to the housing 44 at 51, tightly, in any suitable manner.

The other end of the cable 49, and of tube 50, is disposed in a pull box (not shown) which is disposed at a remote point. It is believed sufficiently obvious as not to require illustration that a stop member would be mounted on the cable 49 which member can also constitute a hand grip for the cable, the stop member cooperating with the spring 48 to retain lever 46 and rod 47 substantially in the positions shown. As will be seen, should a pull be exerted upon the cable 49, this will force the inner end of the rod 47 downwardly, so as to lower the diaphragm 30.

On the lever 17, at any suitable point, as for example, on the weight 18, is disposed a clip 52, retaining a mercoid switch 53. Leads 54 extend from the mercoid switch to a suitable alarm device (not shown), as for instance a bell or light. When the lever 17 is in its normal raised position, the switch 53 is positioned so as to keep the alarm circuit open. However, should the lever 17 swing downwardly to close the valve 11, the change of position of the mercoid switch 53 will cause the circuit to be closed, actuating the alarm.

From the above, it will be observed that in a single, simple, self-contained unit, means are provided for shutting off a supply of gas immediately, and concurrently actuating an alarm device, in the event of any lowering of the flow of gas below a predetermined amount, flooding, or fire, any of these occurrences bringing about an automatic working of the valve and alarm. Additionally, it is seen that means are also embodied in the single, simply arranged unit described for closing the valve by hand from a remote point whenever necessary or desired.

What is claimed is:

1. The combination with a casing having a gas inlet and outlet, a valve swingable into position to close one of these, a diaphragm casing, a diaphragm mounted therein responsive to

changes in gas pressure, and means actuated by the diaphragm to close the valve, of a tubular extension on the diaphragm casing, there being an opening communicating therebetween, a rod slideable in the tubular extension and projecting through the opening, said rod bearing at one end against the diaphragm, a normally restrained spring on the rod, a fusible spacer on the other end of the rod, whereby fusing of the spacer will permit the spring to expand, 10 and a water-soluble spacer on the rod, said tubular extension having a vent opening.

2. In a valve unit actuated by a diaphragm mounted in a diaphragm casing, a tubular extension on the diaphragm casing having a vent in its side wall, there being an opening communicating between the tubular extension and diaphragm casing, spring-restrained means in the tubular extension projecting from the opening, and disposed in position to exert pressure to flex the diaphragm, a water-soluble spacer on the extension and on said means, and a fusible spacer on the extension and on said means, said spacers being positioned to normally restrain said means from pressing engagement against the diaphragm.

3. In a safety device for automatic cut-off valves having a diaphragm mounted in a diaphragm casing, a rod mounted in the diaphragm casing in position to engage the diaphragm at one end, a fusible spacer interposed between the other end of the rod and the diaphragm casing, a soluble spacer carried by the rod adjacent the fusible spacer, and yielding means tending to urge the rod pressingly against the diaphragm on melting of either spacer.

4. The combination with a valve casing having a gas inlet and outlet, a valve swingable into position to close one of these, a diaphragm casing in communication with the valve casing, a diaphragm in the diaphragm casing responsive to changes in pressure, and means actuated by the diaphragm to close the valve, of a rod mounted in the diaphragm casing in position to engage the diaphragm, meltable spacers on the rod positioned to retain the rod in normal position, yielding means tending to urge the rod pressingly against the diaphragm on melting of either spacer, mercoid switch means mounted on the diaphragm actuated valve closing means in circuit with an alarm device, and hand-controlled flexible means for manually closing the valve, comprising a flexible cable, a lever fulcrumed intermediate its ends to the diaphragm casing, the cable being connected to one end of the lever, and a normally spring-restrained rod pivotally connected to the other end of the lever, and extended into the diaphragm casing in position to exert pressure against the diaphragm.
